UNITED STATES PATENT OFFICE.

EZRA E. CLARK, OF NEWTONVILLE, MASSACHUSETTS.

LOCKING MECHANISM FOR DRY-PIPE VALVES.

Application filed July 12, 1922. Serial No. 574,489.

To all whom it may concern:

Be it known that I, EZRA E. CLARK, a citizen of the United States, and resident of Newtonville, county of Middlesex, State of Massachusetts, have invented an Improvement in Locking Mechanism for Dry-Pipe Valves, of which the following description, in connection with the accompanying drawing, is a specification, like characters on the drawing representing like parts.

This invention relates to improvements in dry pipe valves of the type which are employed in automatic sprinkler systems and which include a water valve and an air valve so constructed that the pressure of air confined in the sprinkler system will hold the water valve closed against the pressure of the water in the supply pipes.

These dry pipe valves are further so constructed that a lesser air pressure will hold the water valve closed against a greater pressure.

Dry pipe valves of this general character are provided with means for guiding the valve structure upon release of the air pressure, to a position outside of the waterway so that the water will flow freely from the supply through the outlet of the casing and the connecting pipes to the sprinkler heads. It is desirable that means shall be provided for positively locking the valves in open position so that they cannot be returned to closed position by a reverse flow of the column of water leading to the sprinkler heads, in case the water supply entering the casing is diverted by the opening of a second dry pipe valve, or for any other reason. This has heretofore been accomplished by providing a latch carried by the casing which engages the air valve.

The principal object of the present invention is to provide a novel means for locking the valves in open position in which the locking members are carried respectively upon the valve structure and upon the link mechanism which supports and guides the valve into open position.

A further object of the invention is to provide locking means which will be more readily accessible and, therefore, more easily released when it is desired to restore the valves to closed position.

Another object of the invention is to provide a locking mechanism which will be more certain and effective in operation than those heretofore produced.

Another feature of the invention consists in providing a novel, readily detachable, pivotal connection between the supporting and guiding link or links and the valve to enable the valve to be detached for purposes of cleaning and removal.

Other objects and features of the invention will more fully appear from the following description and the accompanying drawings and will be pointed out particularly in the claims.

In the drawings:

Fig. 1 illustrates in vertical longitudinal section a dry pipe valve embodying a preferred form of my invention;

Fig. 2 is a detail sectional view showing a preferred form of detachable connection of the supporting link to the valve structure; and,

Fig. 3 is a detail elevation of the shaft or pin of the detachable connection illustrated in Fig. 2 and the means for locking the same in place.

The present invention is illustrated herein as applied to the general type of dry pipe valve disclosed in my prior Patent No. 1,300,698, granted April 15, 1919.

The dry pipe valve construction illustrated comprises a body portion or casing 1 which is provided at its upper end with an outlet opening 2 adapted to be connected to an automatic sprinkler system normally containing air under pressure. The lower end of the casing is provided with an opening 3 to be connected with the usual riser or pipe of the water supply which is always under pressure. The openings 2 and 3 preferably are in alinement so that a substantially straight waterway is provided through the casing for the water which is forced therethrough upon unseating of the air and water valves by the release of a sprinkler head and consequent reduction of air pressure in the sprinkler system.

A covered hand hole 4 is provided in one side of the casing through which the valve structure may be inserted and assembled within the casing or removed therefrom. A smaller opening or hand hole 5 having a screw threaded plug 6 is provided to permit the machining of the air valve seat.

In this preferred construction an inlet conduit 7 extends well within the casing in alinement with the opening 2 and is provided with a water valve seat 8 which preferably is secured to the end of the inlet

conduit by a screw threaded connection, the valve seat preferably being normal to the axis of the inlet conduit.

The valve casing is provided with an air valve seat 9 of considerably larger diameter than the water valve seat and which is inclined to the plane of the water valve seat.

The air valve and water valve preferably are joined together in a unitary valve structure and function substantially as a unit in their operative movements.

As illustrated herein the water valve 10 is connected to the air valve 11 by a stud 12 having an enlarged shouldered head 13 provided with a convex face which engages a complementary concaved face in a boss 14 which extends upwardly from the central portion of the water valve 10. A cap or cover 15, which overlies the shouldered portion of the head 13, is secured to the boss by a screw threaded connection. The cap 15 desirably is provided with laterally extending projections 16 adapted to be engaged by a keeper 17 to prevent the cap 25 from rotation when once properly secured in place. Desirably there is a sufficient loose fit between the cap and the head 13 of the stud 12 to permit such movement of the water valve as may be necessary to cause it 30 properly to seat.

Suitable link mechanism is provided to carry the valve structure, when the valve is opened by release of the pressure of air upon the air valve, to a position outside of the waterway. The link mechanism illustrated in the present construction comprises substantially parallel links, one of which is a U-shaped link 18 the lower ends of which are preferably pivotally mounted upon 35 studs 19 upon the portion 7 of the casing forming the waterway. Extensions 20 of said U-shaped link are pivotally connected by a stud 21 to a boss 22 extending downwardly from the under side of the high 40 portion of the valve 11. The U-shaped link 18 is so positioned that when the valve structure is swung to open position the link will be removed from the waterway and will not obstruct the free flow of the water.

50 The lower portion of the air valve 10 is provided with bosses 23 which carry a shaft 24 upon which the upper end of a link 25 is pivotally mounted, the lower end of said link being pivotally mounted upon 55 a shaft 26 mounted in bosses 27 in the lower portion of the casing 1.

The shaft 24 desirably is retained in place by a locking device which can be readily removed to enable the shaft to be withdrawn and the valve structure detached from the link in order that the valve structure may be raised for the purpose of cleaning. A similar locking device may if desired be provided for the shaft 21 which connects the extension 20 of the link 18 to the valve

structure so that the entire valve structure can be readily assembled in and removed from the casing.

A preferred locking device is illustrated herein in Figs. 2 and 3. In this construction the shaft 24 is provided with a pin or key 28 which extends into a recess in one of the lugs 23 of the valve structure. The opposite end of the shaft is provided with a transverse slot 29 which extends inwardly 70 a sufficient distance to cause the end wall 30 of the slot to lie within the face of the lug 23 on the valve structure. A pin 31 extends across the slot a short distance beyond the face of the lug 23. A locking key 32 having a slot 33 extending longitudinally thereof is pivotally and slidably mounted upon the pin 31. The locking key 32 desirably is of the same or a less width than the diameter of the bolt 24 and may if desired be slightly wedge-shaped and provided with a beveled or rounded lower end 34 which will permit it to be rotated about the pin 31 when raised from locking position.

In assembling the device the key 32 is raised and rotated about the pin 31 until it is in axial alignment with the shaft, as illustrated in dotted lines in Fig. 2. The shaft is then introduced through the bosses 23 on the valve structure and the upper end of the link 25. When thus introduced the locking key is rotated into vertical position and forced downwardly into the position illustrated in full lines in Fig. 2 so that it extends at right angles to the axis of the shaft with its side preferably abutting against the lug 23. When it is desired to remove the shaft 24 the locking key 32 may be raised and rotated about the pin 31 until it is in axial alignment with the shaft 24 when the shaft can be readily withdrawn. Thus the locking key can be withdrawn and the shaft removed manually without the use of tools. Inasmuch as the locking key is fixedly secured to the shaft it will not become detached, misplaced or lost. By this construction a convenient means is provided for releasing the link 25 to enable the valve structure to be raised for the purpose of cleaning the valve seat. If the shaft 21 is provided with a similar locking device the entire valve structure can be readily assembled in the casing and removed therefrom.

The effective lengths of the link 25 and the link 18 with its extensions 20 preferably are equal and a plane passing through the centers of the shafts 24 and 26 desirably is substantially parallel to a plane passing through the centers of the studs 19 and shaft 21 so that the links are in effect parallel links.

When the air pressure to which the air valve 11 is subjected is reduced by the opening of the sprinkler head, the pressure of

the water upon the water valve will swing the water and air valve structure from its closed position, which is illustrated in section, to the dotted line position illustrated in the drawing in which position the valve structure is entirely outside of the waterway.

In order to securely lock the valve structure in its open position and prevent the possibility of a back flow of the column of water leading to the sprinklers reseating the valve, the present invention includes locking mechanism for preventing relative movement between the valve structure and the link mechanism. This locking mechanism desirably comprises co-operating interengaging members carried respectively by the valve structure and link mechanism adapted to engage only when the valve is swung substantially to the open position and which 20 when engaged will require manual operation to release the same.

In the preferred embodiment of the invention illustrated a pawl 35 is pivotally mounted upon a stud 36 which extends from a strengthening web 37 which desirably extends substantially diametrically across the air valve. The pawl 35 desirably is provided with a tail 38 which will limit its movement by engagement with the back or upper face of the air valve, and prevent placing the pawl in an inoperative position. The other end of the pawl is adapted to engage a suitable shoulder upon the link mechanism.

As illustrated herein the link 25 is provided with a projection 39 having a shoulder 40 adapted to be engaged by the end 41 of the pawl 35 when the valves are thrown to open position, illustrated in dotted lines. The end portion of the pawl 35, however, desirably extends over and rests upon the curved upper surface of the projection 39 when the valves are in closed position.

In the operation of the device, therefore, the rotative movement of the projection 39 about the axis of the shoulder 40, as the valve is swung from closed to open position, causes the shoulder 40 to pass beneath and beyond the end 41 of the pawl 35 so that the end of the pawl will drop into alignment with the shoulder, as illustrated in dotted lines, and positively prevent the return movement of the valve.

In order again to reseat the valve it is necessary for the operator to remove the cover of the aperture 4 and lift the pawl out of engagement before restoring the valve to seated position.

It will be noted that the pawl is so positioned that it can be readily reached in this manner and is more conveniently accessible to the operator than in constructions heretofore produced.

It will be understood that the embodiment of the invention disclosed herein is of an

illustrative character and is not restrictive and that various changes in form, construction and arrangement of parts may be made within the spirit and scope of the following claims.

Having thus described my invention, what I claim as new, and desire to secure by Letters Patent, is:

1. A dry pipe valve comprising a casing having a waterway therethrough and provided with a water valve seat and an air valve seat, a valve structure including an air valve and a water valve, link mechanism connecting said valve structure to said casing and acting upon unseating of the valves to guide the valve structure to open position outside of the waterway and locking members carried respectively by said link mechanism and the movable valve structure arranged to engage when the valves are swung to open position and thereby to prevent closing of said valves.

2. A dry pipe valve comprising a casing having a waterway therethrough and provided with a water valve seat and an air valve seat, a valve structure including an air valve and a water valve, link mechanism connecting said valve structure to said casing and acting upon unseating of the valves to guide the valve structure to open position outside of the waterway and co-operating interengaging members carried respectively by the movable link mechanism and said valve structure arranged to engage when the valves are swung to open position and thereby to prevent closing of said valves.

3. A dry pipe valve comprising a casing having a waterway therethrough and provided with a water valve seat and an air valve seat, a valve structure including an air valve and a water valve, link mechanism connecting said valve structure to said casing and acting upon unseating of the valves to guide the valve structure to open position outside of the waterway and locking mechanism including a shoulder on said link mechanism and a locking pawl pivotally mounted upon the movable valve structure operable to engage said shoulder when said valves are swung to open position and thereby to prevent closing of said valves.

4. A dry pipe valve comprising a casing having a waterway therethrough and provided with a water valve seat and an air valve seat, a water valve and an air valve connected to form a unitary valve structure, the water valve being of less area than the air valve, a pair of links pivotally connected at one end to said air valve and at the other end to said casing, a pawl pivotally mounted on said air valve and a shoulder upon one of said links positioned to engage said pawl when the valves are swung to open position and operable to prevent closing of said valves.

5. A dry pipe valve comprising a casing having a waterway therethrough, a water valve and an air valve connected to form a unitary valve structure, the water valve being of less area than the air valve, the planes of the differential valves being oblique to each other, seats for said valves, link members of equal length pivoted to provide a parallel link system to carry the differential valve structure and to guide the valve

structure from seated to open position, a pawl pivotally mounted on said valve structure and a shoulder upon one of said links positioned to be engaged by said pawl when said valves are swung to open position and thereby to prevent closing of said valves. 15

In testimony whereof, I have signed my name to this specification.

EZRA E. CLARK.
